FLOOR RACK FOR REFRIGERATOR CARS

Charles David Bonsall, Pittsburgh, Pa., assignor
to Standard Railway Equipment Manufacturing Company, Chicago, Ill., a corporation of
Delaware

Application March 3, 1938, Serial No. 193,742

9 Claims. (Cl. 105—375)

The invention relates to insulated refrigerator cars used to transport perishable commodities, such as vegetables, fruits, berries, meats, eggs, frozen fish, etc., and to maintain such commodities while in transit within a predetermined range of temperature, thus necessitating the use of a cooling means in the summer and a heating means in the winter. It has been found that perishable commodities which have not been allowed to get too cold (freeze) or too hot (bake) have a high market value because they have a longer storage life.

The object of the invention is to provide a floor rack for a refrigerator car which is very strong to support vertical loads and has great strength in a horizontal direction (to resist the tendency of a shifting load to move the floor rack sidewise) without materially retarding the flow of air below the floor rack or materially reducing the amount of air flow through the floor rack.

In the drawings:

Figs. 1 and 2 are longitudinal and transverse sections respectively of a refrigerator car showing the correlation of my device to the other elements of a car.

Fig. 3 is a perspective view of my improved floor rack.

Fig. 4 is a section on line 4—4 of Fig. 3.

Fig. 5 shows a modified construction.

Fig. 6 is a perspective view of a modification of my floor rack.

Fig. 7 is a section on line 7—7 of Fig. 6.

Fig. 8 is a section on line 8—8 of Fig. 6.

Fig. 9 is a perspective view of a modification of my floor rack.

Fig. 10 is a section on line 10—10 of Fig. 9.

Fig. 11 is a section on line 11—11 of Fig. 9.

Fig. 12 is a modification of the construction shown in Fig. 3.

Fig. 13 is a section on line 13—13 of Fig. 12.

Fig. 14 is a section on line 14—14 of Fig. 12.

In the form of my invention illustrated the refrigerator car is provided with a bulkhead 2 separating the refrigerant chamber 3 from the lading compartment 4. The bulkhead 2 is provided with an aperture 5 adjacent the floor 6 of the car and an aperture 7 adjacent the ceiling 8 of the car with a solid wall 9 therebetween.

A refrigerant is supported by the grates 10 in the refrigerant chamber 3 in spaced relation to the floor 6 of the car and the basket (or netting) 11 spaces the refrigerant from the end wall 12 and bulkhead 2 to provide the flues 13—14. The apertured floor rack 15 supports the lading so as

to provide the space or flue 16 which communicates with the flues 13—14. A refrigerant, such as ice, in the refrigerant chamber induces a convection circulation of air from the flues 13—14 through the flue space 16 and the aperture 17 in the floor rack 15, and as the air is warmed by the lading, it rises and passes through the bulkhead upper opening 7 and thence through the flues 13—14, and being cooled by the refrigerant, repeats the convection cycle.

Figs. 3 and 4 show my improved floor rack 15 comprising a foraminous floor 28 supported upon the insulated or main floor 6 of the car by a plurality of parallel stringers 21 to provide the plurality of spaces or flues 16 between the foraminous floor 28 and the insulated or main floor 6 which communicate with the flues 13—14 in the refrigerant chamber.

Each stringer 21 preferably is made of a metallic plate pressed to form a channel shaped member comprising spaced apart walls 24 connected by a web 25 and outwardly projecting upper lateral flanges 26. Such a stringer provides a very strong member to support vertical loads, especially when the walls are prevented from spreading. The walls are preferably provided with apertures 27 for air circulation. The spaces 28 between the walls 24 also provide flues which communicate with the flues 13—14.

The foraminous floor 15 comprises a plurality of metallic panels 30 with the margins of each panel preferably downwardly offset as at 31 and underlying a margin of an adjacent panel and secured thereto preferably by welding. Such a construction provides a smooth upper surface for the foraminous floor which is essential in a refrigerator car because any projection on the floor would jag a lading container when the load is shifted or when the load is being squeezed in place by the wedge bracing at the doorway. This wedge bracing compresses the load in opposite directions toward the ends of the car to obtain a compact or tight lading to eliminate shifting of the lading in transit. The underlying margins of some of said panels are formed with a flange 32 which preferably rests upon and is secured to the stringers 21 to provide a plurality of beams between the stringers 21. The flanges 32 may be welded directly to the stringers.

The flanges are preferably provided with re-flanges 33 to materially increase the tension sides of the beams and increase the bearing areas of beams upon the stringers; also to provide means for riveting the beams to the stringers.

and to facilitate welding of these reflanges to the stringers.

The foraminous floor 15 comprises an apertured metallic sheet and some of the apertures 17 are preferably positioned over the reflanges 33 of the flanges 32 to facilitate riveting or welding the flanges (or reflanges) to the stringers.

The apertures 17 are preferably formed with depending peripherical flanges 35 to strengthen 10 the metallic sheet between adjacent flanges 32. These flanges preferably extend from one flange 32 to adjacent another flange 32.

Fig. 5 shows a modification wherein each of 15 the panels is provided with a relatively deep marginal flange 40 attached to the stringers 21 and a relatively shallow marginal flange 41 secured to the deep flange 40 of the adjacent panel, preferably by welded material at 42.

Figs. 6, 7 and 8 show a modification of my 20 invention in which the foraminous floor comprises a continuous perforated metallic plate 50 supported on and secured to a plurality of beams 51 extending between the stringers 52. The plate 50 is provided with a plurality of integrally 25 formed rib-like depressions 53 extending transversely to the beams 51, the purpose being to stiffen the plate over the span between said beams. The apertures 58 in the plate 50 are 30 preferably formed with depending peripherical flanges to strengthen the plate 50 between the beams 51. These flanges preferably extend from one beam 51 to adjacent another beam 51. The beams 51 are offset to provide depressions 57 for seating the strengthening ribs 53. The beams 51 35 are preferably formed with a vertical web 54, a horizontal flange 55 for securing, by welding or riveting, to the plate 50, and a horizontal flange 56 for securing to the stringer 52.

Figs. 9, 10 and 11 show a modification of my 40 invention in which the foraminous floor comprises a continuous perforated metallic plate 60 supported on and secured to a plurality of beams 61 arranged substantially parallel to the stringers 62. The apertures 67 in the plate 60 are 45 preferably formed with depending peripherical flanges to strengthen the plate 60 between the beams 61. These flanges preferably extend from one beam 61 to adjacent another beam 61. Said beams 61 are preferably formed with a vertical web 65, an upper horizontal flange 64 and a lower horizontal flange 65 and rest upon and are secured to a plurality of preferably similar beams 66 arranged transversely to said upper beams 61. The lower beams 66 rest upon and 50 are secured to the stringers 62. The distance between the upper beam 61 is less than the distance between the beams 66 and the distance between the beams 66 is less than the distance between the stringers 62.

Figs. 12-14 show a modification of Fig. 3 in which have been added depressed stiffeners 70 extending across several panels 30 transversely to the flanges 32.

The drawings illustrate the floor rack supported on channel-shaped stringers made of a metallic plate. Other types of stringers, such as, for example, wood, may be used in their place.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car, the combination of an insulated floor, a foraminous floor, a plurality of parallel stringers supporting the foraminous floor above the insulated floor to provide a space between said floors, and means to induce an air current in said space, said foraminous floor comprising a plurality of perforated metallic panels with a margin of each panel underlying a margin of an adjacent panel and secured thereto, the underlying margin of each panel formed with a flange, said flanges extending between and secured to said stringers.

2. In a refrigerator car, the combination of an insulated floor, a foraminous floor, a plurality of parallel stringers supporting the foraminous floor above the insulated floor to provide a space between said floors, and means to induce an air current in said space, said foraminous floor comprising a plurality of perforated metallic panels with a margin of each panel underlying a margin of an adjacent panel and secured thereto, the underlying margin of each panel formed with a flange provided with a reflare, said reflanges extending between and secured to said stringers.

3. In a refrigerator car, the combination of an insulated floor, a foraminous floor, a plurality of parallel stringers supporting the foraminous floor above the insulated floor to provide a space between said floors, and means to induce an air current in said space, each of said stringers comprising substantially parallel walls connected by a web, said foraminous floor comprising a plurality of perforated metallic panels with a margin of each panel underlying a margin of an adjacent panel and secured thereto, the underlying margin of each panel formed with a flange, said flanges extending between said stringers and secured to both walls thereof.

4. In a refrigerator car, the combination of an insulated floor, a foraminous floor, a plurality of parallel stringers supporting the foraminous floor above the insulated floor to provide a space between said floors, and means to induce an air current in said space, said foraminous floor comprising a plurality of perforated metallic panels with a margin of each panel underlying a margin of an adjacent panel and secured thereto, the underlying margin of each panel formed with a flange provided with a reflare, said reflanges extending between and secured to said stringers, said foraminous floor provided with apertures above the intersections of the reflanges with the stringers to facilitate securing the reflanges to the stringers.

5. In a refrigerator car, the combination of an insulated floor, a foraminous floor, a plurality of parallel stringers supporting the foraminous floor above the insulated floor to provide a space between said floors, and means to induce an air current in said space, said foraminous floor comprising a plurality of perforated metallic panels with a margin of each panel downwardly offset and underlying a margin of an adjacent panel and secured thereto to provide a smooth upper surface, the underlying margin of each panel formed with a flange, said flanges extending between and secured to said stringers.

6. In a refrigerator car, the combination of an insulated floor, a foraminous floor, a plurality of parallel stringers supporting the foraminous floor above the insulated floor to provide a space between said floors, and means to induce an air current in said space, said foraminous

floor comprising a plurality of perforated metallic panels, each of said panels having a relatively deep marginal flange secured to the stringers and a relatively shallow marginal flange secured to the deep flange of the adjacent panel.

5. A structure as defined in claim 1 wherein a plurality of said metallic panels are formed with a continuous corrugation extending normally to and crossing the flanges of these metallic panels to form stiffeners therebetween.

10. In a refrigerator car, the combination of an insulated floor, a foraminous floor, a plurality of parallel stringers supporting the foraminous floor above the insulated floor to provide a space between said floors, and means to induce 15 an air current in said space, said foraminous

floor comprising a plurality of perforated metallic panels with a margin of each panel formed with a depending flange extending between and secured to said stringers, the margin of each panel opposite the flanged margin thereof being secured to the flanged margin of the adjacent panel.

9. A structure as defined in claim 8 wherein said metallic panels are provided with apertures extending substantially between the depending flanges of adjacent metallic sheets with the portions of the metallic sheets around said apertures being bent to form continuous flanges which function as beams between said depending flanges.

15 CHARLES DAVID BONSALL.
